UNITED STATES PATENT OFFICE

CLINTON DOWLING, OF WASHINGTON, DISTRICT OF COLUMBIA, ASSIGNOR TO DOWLING'S GOLF GAMES, INC., A CORPORATION OF DELAWARE

TOY

Application filed March 7, 1930. Serial No. 434,028.

This invention relates to amusement devices intended for use by those interested in golf, although it will be found to be adaptable for use by others.

Briefly stated, the invention forming the subject of this application contemplates a novel spinning toy in which the rotatable element such, for example, as a freely operated pointer is caused to play over the selectively exposed legends on an adjustable disk positioned beneath the pointer, the legends on the disk being closely identified with golf and indicating the various plays therein and serving as a means of determining the next position of the legend bearing disk.

Another aim of the invention is to provide a game of the character specified which is fascinating, cheap to manufacture and simple to play.

Other objects and advantages will be apparent during the course of the following description.

In the accompanying drawings forming a part of this application and in which like numerals are employed to designate like parts throughout the same,

Figure 1 is a plan view of the toy in what might be said to be initial position,

Figure 2 is a similar view of the toy with the legend bearing disk in an intermediate position,

Figure 3 is a plan view of the pointer with the legend bearing disk in final or putting position,

Figure 4 is a plan view of the toy with the face plate removed,

Figure 5 is a vertical sectional view taken on line 5-5 of Figure 3,

Figure 6 is a detail sectional view taken on line 6-6 of Figure 3,

Figure 7 is an enlarged plan view of the legend bearing disk detached.

In the drawings wherein for the purpose of illustration is shown a preferred embodiment of the invention, the numerals 6 and 8 designate spaced face and supporting plates, respectively, between which a legend bearing disk 9 is rotatably mounted through the medium of a spindle 10. Of course, suitable means such as washers may be positioned be-

tween the spaced plates 6 and 8 to allow of the ready adjustment of the legend bearing disk 9 and at the same time to hold the same against undesired shifting.

As shown in Figure 7, the disk 9 has the peripheral portion thereof formed with radial groups of legends corresponding to the plays in golf and the arrangement of the groups of legends is such that one legend of each group may be seen through the annular series of radially disposed sight openings 11 in the face plate.

The legend bearing disk 9 is shown to be provided with a radial extension or handle 14 terminating beyond the edges of the face and supporting plates 6 and 8, respectively, for manual engagement, this feature of the invention providing a simple means by which the disk may be turned to present a new set of legends to the sight openings 11. 70

Figures 1 and 2 illustrate that the face plate or member 6 is provided with a transverse sight opening 20 affording a view of the golf shot representing symbols on the extension 14, and as is believed to be apparent, the symbols on the extension 14 may be selectively brought in line with the arrow 22 by manual adjustment of the extension.

The initial position of the legend bearing disk or member 9 is shown in Figure 1 in which the word "driver" is positioned in line or register with the arrow 22. Such an adjustment of the disk 9 positions one legend of each group of legends to be seen through the sight openings 11, while the remaining legends of the various groups of legends are concealed beneath the face plate 6.

When the legend bearing disk has been placed in its initial position as shown in Figure 1, the player spins the pointer 18 to cause the same to play over the exposed legends and the particular legend to which the pointer is closest when it stops indicates the length of the imaginary drive. For example, in Figure 1, the pointer 18 indicates 95 an imaginary drive of 295 yards.

At this point, attention might be invited to the rules of the game in accordance with which rules the player whose turn it is spins the pointer 18 and should his imaginary 100

drive be less than 250 yards his second imaginary shot will be with the "brassie," indicating, of course, that the symbol "brassie" on the extension 14 is to be brought into registration with the arrow 22.

Should the pointer 18, on the initial spinning thereof, point to a yardage ranging from 250 or 300, the disk 9, and more particularly the extension 14 thereof, will be positioned with the symbol "midiron" in registration with the fixed arrow or indicator 22 to expose a series of legends different from those seen when the disk 9 is in the "brassie" position.

15 When, on the initial spinning of the pointer 18, the imaginary drive exceeds 300 yards, the disk 9 will next be placed in the "mashie" position. That is to say, the word "Mashie" on the extension 14 will be brought into register with the pointer 22 with the result that a new series of legends are exposed, while the remaining legends will remain concealed.

16 If the pointer 18 indicates the imaginary shot to be in a trap or to have a bad lie, the player is penalized one stroke and is required to spin the pointer 18 again.

17 If, as a result of spinning of the pointer 18 while the disk is in the "mashie" position, 30 the spinner points to a legend indicating that the imaginary ball has overrun or shot off the green, the player is, on his next shot, required to position the extension 14 so that the symbol "Mashie niblick" will be in register with the arrow 14. Thus, in effect, the player is caused to lose a stroke.

18 A tally disk 28 is positioned between the plates 6 and 8 and is rotatably supported by a spindle 30 which, in addition to functioning as such, will serve as a means for connecting the face and supporting plates. The tally disk 28 bears series of numbers adapted to be seen singly through the sight opening 32 in the face plate 6. Through the medium 40 of the tally disk, the number of times required to spin the pointer 18 to complete an imaginary hole may be recorded.

19 A tally disk 24 positioned between the face plate 6 and the supporting plate 8 is 50 mounted on a spindle 26 corresponding in purpose to the spindle 30. The disk 24 bears numbers seen through a sight opening 34 to indicate the number of holes played.

20 In operation, the radial extension 14 of the 55 initial bearing disk 9 is positioned to align the symbol "Driver" with the arrow 22, after which the pointer 18 is spun and the number to which the same is found to be pointing when it stops will determine the next position of the disk 9.

21 If a number less than 250 appears in the sight opening to which the arrow 18 points as a result of the initial spinning thereof, the player will turn the disk 9, through the extension 14 thereof, so that the symbol "Bras-

sie" will appear in line with the arrow 22. The pointer is now spun again and the legend to which the same is found to be pointing at the completion of the spinning indicates the next position of the adjustable disk.

22 For example, if the arrow 14 points to the symbol "Green" the disk 9 is turned to present the symbol "Putter" to the arrow 22, this position being illustrated in Figure 3. The player now spins the pointer 18 again and if the same comes to rest pointing to the legend "In" the hole is regarded as having been completed or made and the number of times it was necessary to operate the pointer 18 determines the score of the player for a particular hole.

23 The invention forming the subject of this application is capable of a wide variety of expressions involving slightly different arrangements and it is therefore to be understood that the form of invention herewith shown and described is to be taken merely as a preferred example of the same and that such minor changes in arrangement and construction of parts will be made as will remain within the spirit of the invention and the scope of what is claimed.

24 Having thus described the invention, what is claimed is:

25 1. In a simulated golf game, a substantially disc-shaped member having an annular series of groups of legends representing plays in a golf game and also being provided with a radial extension bearing symbols corresponding to shots in a golf game, a second member in superposed relation to said first member and having an annular series of circumferentially spaced sight openings to simultaneously frame and expose one legend of each group of legends and thereby form a circle of individual legends, said second member also being provided with a marker with which the golf shot representing symbols are adapted to separately register, and a pivotally mounted spinner adapted to play about the individually and simultaneously exposed legends visible through said sight openings and dictating the golf shot indicating symbol that shall register with the marker on said second member for subsequent play.

26 2. In a simulated golf game, a member having a group of symbols representing shots in a golf game, a second member having a marker with which the golf shot representing symbols of said group of symbols are adapted to separately register to temporarily fix the position of one of said members with respect to the other member, one of said members having an annular series of groups of legends representing plays in a golf game and the other member having circumferentially spaced sight openings to simultaneously frame and expose one legend of each group

of legends and thereby form a circle of individual legends, and a chance device dictating the particular golf shot indicating symbol of said group of symbols with which said 5 marker shall register for subsequent play.

In testimony whereof I affix my signature.

CLINTON DOWLING.
